UNITED STATES PATENT OFFICE.

BAY M. BROWN, OF YONKERS, NEW YORK, ASSIGNOR, BY MESNE ASSIGNMENTS, TO
AMERICAN THROTTLE COMPANY, OF NEW YORK, N. Y., A CORPORATION OF NEW
YORK.

BALANCED MULTIPLE THROTTLE.

Application filed April 21, 1925. Serial No. 24,802.

This invention relates to locomotives equipped with superheaters and is for an improvement on the invention disclosed and claimed in my United States application for Patent 650,850, filed on July 11, 1923. The object of the present invention is to provide an improved form of the arrangement which shall be operable with less effort, and in which some of the stresses to which the former arrangement subjects the apparatus are eliminated.

The invention is illustrated in the three sheets of drawings herewith, in which Fig. 1 is a sectional view on line 1—1 of Fig. 2 and represents the upper portion of the front end of a locomotive equipped with my invention; Fig. 2 is a section on line 2—2 of Fig. 3; Fig. 3 is a section on line 3—3 of Fig. 1; Fig. 4 is a view of the valves employed in my invention shown in a certain position, the elements actuating the valves being omitted in this figure for the sake of clarity; Fig. 5 is a section on line 5—5 of Fig. 1 and Fig. 6 is a view corresponding to a portion of Fig. 2 and illustrating a modification.

All of the figures are on the same scale. Parts not necessary for an understanding of the invention are broken away and omitted.

The tube sheet 1 of the locomotive divides the steam and water space 2 from the smokebox 3. Flues 4—4 extend toward the rear from flue sheet 1 and accommodate the tubular superheater elements 5—5. The ends of these elements are bent upward at the forward end and secured to the header 6. This header has a space 7, communicating with the steam space of the boiler by means of pipe 11 and connection 12, and fingers or subheaders or fingers 9—9 extending forward from space 7. Other subheaders or fingers 10—10 are intermeshed with the subheaders 9—9, but do not communicate directly with them. The two ends of each element or unit 5 communicate respectively with a subheader 9 and a subheader 10. At their forward ends the subheaders 10—10 open into the superheated steam chamber 7a.

The general arrangement so far described is well known and widely used. Its action may be briefly stated as follows:

Steam from the boiler flows through pipe 11, connection 12, saturated steam space 7, into the subheaders 9. From there it flows

thru the several superheater elements 5, in which it is superheated by the gases passing through the flues 4, and by which it is delivered to the subheaders 10, which lead it to the superheated steam chamber 7a.

It is not new to arrange the throttle controlling the flow of steam to the steam chest of the locomotive between the superheater header and the steam chest. In the application referred to above a novel form and arrangement for such controlling means is described and claimed, consisting essentially of a plurality of relatively small valves. In my invention I use this same idea of a plurality of small valves. They are shown in the drawings at 13—13. These valves are seated on valve seats 14—14 of the bushings 14a—14a in the partition 15, which divides the superheated steam chamber horizontally. The superheated subheaders 10—10 open into the space 16 above the partition 15. From the space below the partition 15 the usual two steam pipes 17—17 extend to the steam chests.

A second partition, 18, parallel to partition 15, divides off the lower portion 19 of the space within the superheated chamber 7a. In this partition 18 are a number of cylindrical openings 20, which are alined with the bushings 14a and are slightly smaller in area. The valves 13 each comprise a head 13a, a stem 13b, and a piston 13c. The pistons 13c reciprocate in the openings 20.

The valve stems 13b have each a slot 13d, into which extends the operating finger 21. The fingers 21 are all fixed to the shaft 22, which extends through the header, one end lying in a bearing 23, and the other extending through a stuffing box 24 to the outside of the header and smoke box. The shaft 22 has secured to its outer end an arm 26, to which is pivotally connected the rod 27 which extends back to the cab. A longitudinal movement of the rod 27 evidently results in a rotary or rocking motion of the shaft 22, so that the valves 13 can be actuated from the cab.

An inspection of Figs. 1 and 4 will show that the slots 13d are not all of the same length. In Fig. 1, where the valves are all shown in closed position, the fingers will be seen to be in engagement with the lower end of each slot, and the lower ends all to be on a line. In Fig. 4 the valves are all shown

in their open position, the fingers being omitted for the sake of showing more clearly the difference in the length of the slots. These fingers at this time engage the upper ends of the slots. The valves, it should be noted, are open by different amounts.

In the form shown the two outermost valves of the series of seven valves are opened to the greatest extent, and are, during the opening rotary motion of shaft 22, the first to open. The distance to which the other valves are open decreases progressively toward the center, and the valves will open in this order. The order of opening may be made a different one, and different valves may be selected to open farther. This phase of the disclosure is old in the above mentioned application, and no claims to it per se are made herein.

Some difficulty has been experienced in practice in connection with the manipulation of the valves. It has been found that even with the valves made of fairly small size a considerable effort is required to open the first one of them. If they open in pairs the effort is correspondingly greater, and in any case it may be great enough to spring or injure the operating mechanism.

To obviate this, I utilize a relatively small auxiliary balancing valve 28. In the arrangement illustrated this is placed at one end of the header, although it may obviously be put in some other position. This valve is similar to those of the series. It is operated by a finger on shaft 22, engaging a slot in its stem. The opening it controls however does not lead to the middle portion of the superheated steam space but into a passage divided off by vertical partitions 29 and 30 and horizontal partition 31, and opening into the portion 19 at the bottom of the superheated steam space.

The first motion of the shaft 22 opens valve 28. This valve being small no great effort is required and no part of the operating mechanism is in danger of being strained beyond the allowable amount.

This movement of valve 28 admits steam to chamber 19, whereby the entire series of valves becomes balanced and all of them are readily opened in turn. The chamber 19 is not large, and the time consumed before the valves become balanced is negligible.

In order to grant ready access to the valves for purposes of insertion, grinding in, inspection, or removal, openings 32 are made in the top wall of the header, one in line with each valve, which openings are normally closed by covers 33. The smokebox shell is provided with corresponding holes 34, normally closed by covers 35.

In the variation shown in Fig. 6, the fingers 21^a do not engage slots, but to raise the valves engage the projecting extensions

36 on the lower ends of the valves. The difference in the time and extent of the opening of the valves is brought about by making said extensions of different lengths, the fingers 21^a all being alined. Obviously the extensions could all be made of the same length and the angular setting of the fingers on the shaft varied. In this form, a further means of guiding the valves is shown, consisting in the upward extensions 37 of the valves, sliding into the recesses 38 of the covers 33^a. This form of the valve actuating means, it will be noted, lacks the feature of positively seating the valves when they close. The seating is brought about by gravity, aided toward the end of the closing movement by the steam.

What I claim is:

1. In apparatus of the class described, the combination of an elongated horizontal chamber for superheated steam; two horizontal partitions dividing the chamber into three spaces; means to deliver the steam into the top chamber and to take it off from the middle chamber; a passage from the top chamber to the bottom chamber; a valve controlling said passage and opening toward the top chamber; a stem on said valve; there being a row of ports in the upper partition and a corresponding and alined row of openings in the lower partition; valves opening toward the top space controlling the ports and having stems bearing portions closing and reciprocating in the corresponding openings in the lower partition; all of said valve stems being in line; a rotatable shaft adjacent and parallel to the row of valve stems; means to give the rod a rotary motion; means secured to the rod engaging each valve stem and adapted to actuate the valve; said means being arranged to open the first-named valve ahead of all the others.

2. In apparatus of the class described, the combination of an elongated horizontal chamber for superheated steam, two horizontal partitions dividing the chamber into three spaces; means to deliver the steam into the top chamber and to take it off from the middle chamber; a passage from the top chamber to the bottom chamber; a valve controlling said passage and opening toward the top chamber; the upper partition having a series of ports and the lower partition having a corresponding series of cylindrical openings alined with the ports; valves opening toward the top space controlling the ports each having connected to it a piston reciprocating in the corresponding cylindrical opening; and manually operable means to actuate the valves so arranged that the opening movement causes the first-named valve to open ahead of all the others.

RAY M. BROWN.
